R. L. STOVER

SPARK PLUG

Filed July 18, 1923

Patented June 23, 1925.

UNITED STATES PATENT OFFICE.

ROY LITTRRELL STOVER, OF OKLAHOMA CITY, OKLAHOMA.

SPARK PLUG.

Application filed July 18, 1923. Serial No. 652,396.

To all whom it may concern:

Be it known that I, ROY LITTRRELL STOVER, a citizen of the United States, and resident of Oklahoma City, in the county of Oklahoma and State of Oklahoma, have invented certain new and useful Improvements in Spark Plugs, of which the following is a specification.

This invention relates to spark plugs especially adapted for use on internal combustion engines.

Briefly stated an important object of this invention is to provide a spark plug having simple means to combat excess oil in the combustion chamber of the engine and to create an extremely hot and well distributed spark by means of which complete combustion is assured.

A further object is to provide a spark plug in which the heat resulting from combustion is utilized to burn the oil on the spark plugs and thereby allow the spark plug to continue to operate.

A further object is to provide a spark plug which is of highly simplified construction, desirable in use and cheap to manufacture.

Other objects and advantages will be apparent during the course of the following description.

In the accompanying drawing forming a part of this application and in which like numerals are employed to designate like parts throughout the same,

Figure 1 is a side elevation of the improved spark plug in use,

Figure 2 is a vertical sectional view through the same,

Figure 3 is a detail vertical sectional view through a slight modification of the invention.

In the drawing wherein, for the purpose of illustration is shown a preferred embodiment of the invention, the numeral 5 designates a cylinder having the usual combustion chamber 6 and a piston 7 is mounted for reciprocation in the cylinder, all of which is illustrated in Figure 1.

The improved spark plug consists of a shell generally designated by the numeral 10 and having its forward portion threaded as indicated at 11 for attachment to the motor in the manner illustrated in Figure 1.

In carrying out the invention the shell 11 is provided at its forward end with an integral tubular extension or electrode 12

formed of rather thin metal so that the same will readily absorb the heat incident to combustion and will therefore burn any oil which may accumulate thereon.

If the cylinder to which the improved spark plug is connected is especially oily the exterior of the tubular electrode may be provided with a series of annular fins 14 which readily heat and thereby efficiently burn the oil accumulated on the shell. It will be seen with reference to Figure 2 that the upper and lower surfaces and the outer edges of the fins 14 are exposed to the heat thus causing the oil to become quickly heated and assist in retaining a sufficient amount of heat to prevent oil from accumulating thereon.

Also it will be seen that the oil is prevented from dripping down the outer surface of the shell and onto the lower end of the tubular electrode which constitutes one side of a spark gap.

Figure 2 illustrates that the central electrode 16 is extended through an insulator 17 and has its forward portion threaded for engagement with the boss 18 of a concavo-convex baffle 20, the said baffle being formed with an annular flange 21 which constitutes one side of the spark gap. In carrying out the invention the concavo-convex baffle and electrode is held upon the stem or center electrode 16 by a nut 25 and as the concavo-convex baffle and electrode 20 is threaded upon the stem the spark gap may be readily adjusted.

As the annular flange 21 is arranged directly in advance of the forward end of the tubular electrode 12 an annular spark gap is provided by means of which a hot and well distributed spark is provided. By reason of the annular spark gap, the flame resulting from the spark is distributed over the entire combustion chamber to insure the complete combustion of the compressed fuel.

The convex side of the electrode 20 is presented upwardly so as to provide an inclined drain by means of which any oil which enters the shell 10 may be returned to the combustion chamber.

Figure 2 illustrates that the stem 16 is provided rearwardly of the electrode 20 and within the tubular electrode 12 with an annular enlargement 30 in the form of a truncated cone, the base of which is arranged to obstruct the entrance of oil into the shell. That is to say the lower side of the annular

enlargement is arranged at right angles to the axis of the stem 16 while the upper side of the annular enlargement 30 inclines downwardly or is extended diagonally with respect to the axis of the stem 16 so as to allow the oil to freely drain should any enter the shell.

Also the inner side of the shell is provided rearwardly of the annular enlargement 30 with an inwardly projecting annular rib 32 which cooperates with the annular enlargement 30 in preventing the entrance of oil into the shell. It will be seen that the inwardly projecting annular rib 32 is gradually tapered toward its inner free end and is inclined downwardly so as to obstruct the entrance of oil into the shell and to allow of complete discharge of the oil. As the inwardly projecting annular rib 32 is rather thin it will become highly heated and will quickly burn any oil which may accumulate thereon.

Particular attention is invited to the fact that the concavo-convex formation of the electrode 20 not only provides for the escape of oil but also prevents the warping of the electrode as the result of the heat with which the same necessarily comes in contact.

In operation the members 30 and 32 are called upon especially when the motor is first started and until the electrode 20 and the tubular electrode 12 have become sufficiently heated by combustion to dry any oil coming in contact with their surfaces. It will be seen also that the annular fin 14 prevents oil from flowing downwardly on the outer surface of the tubular electrode 12 and then entering the tubular electrode.

If desired the spark plug may be constructed as illustrated in Figure 3 wherein the shell is designated by the numeral 40 and is provided with a tubular electrode 42. In this case the tubular electrode 42 is not provided with an annular fin as in the case of the construction illustrated in Figure 2 and this form of invention is especially designed for use where the spark plug is not exposed to the splashing of oil due to the reciprocation of the piston in the cylinder.

The stem 47 may be provided with an integral concavo-convex baffle and electrode 48 having its outer edge formed with an annular electrode or flange 49 which cooperates with the forward end of the tubular electrode 42 in the formation of an annular spark gap. In this case also the inner side of the shell is provided with an inwardly projecting annular rib 50 beveled to an edge and directed downwardly so as to obstruct the entrance of oil and to allow of the free discharge of the same. The stem is pro-

vided rearwardly of the concavo-convex member 48 with an annular enlargement 52, the forward side of which is extended at right angles to the axis of the stem while the rear side is inclined outwardly.

It will be seen that one of the most important features of the invention resides in the fact that the concavo-convex electrode in advance of the tubular shell is of a greater diameter than the tubular electrode so that oil splashing rearwardly will not be permitted to enter the tubular electrode and herein lies one of the most important features of the invention.

Furthermore convex surface on the upper or rear side of the electrode 20 causes the spark to spread over a wide area in the combustion chamber and thereby assures complete combustion of the fuel.

The usual packing means and nuts therefor may be employed and it might be stated that in the form of the invention illustrated in Figure 3 the packing may be varied as to thickness to provide for the adjustment of the spark gap.

The foregoing illustrates that the invention forming the subject matter of this application is capable of a wide variety of mechanical expressions and it is therefore to be understood that the forms of the invention herewith shown and described are to be taken as preferred examples of the same and that such minor changes in arrangement and construction of parts may be made as will remain within the spirit of the invention and the scope of what is claimed.

Having thus described the invention, what is claimed is:—

1. A spark plug comprising a shell having a tubular electrode, a stem extending centrally through the shell and having its forward end provided with a combined electrode and concavo-convex baffle, the edge portion of said combined electrode and concavo-convex baffle being provided with a flat annular flange arranged in advance of said tubular electrode and being greater in diameter than the tubular electrode and extending beyond the sides of the tubular electrode to obstruct the free movement of oil into the tubular electrode, the shell being provided at the rear end of said tubular electrode with an internal annular flange having its upper and lower surfaces inclined toward the forward end of the stem.

2. The construction set forth in claim 1, said stem being provided in advance of said internal annular flange with an annular enlargement, the upper surface of which is inclined.

ROY LITRELL STOVER.
